UNITED STATES PATENT OFFICE.

HARPER F. SMITH, OF PHILADELPHIA, PENNSYLVANIA.

METHOD OF CONTROLLING COMBUSTION.

SPECIFICATION forming part of Letters Patent No. 759,038, dated May 3, 1904.

Application filed November 24, 1903. Serial No. 182,540. (No model.)

To all whom it may concern:

Be it known that I, HARPER F. SMITH, a citizen of the United States, residing in the city and county of Philadelphia, State of Pennsylvania, have invented a new and useful Improvement in Methods of Controlling Combustion, of which the following is a specification.

My invention relates to a method of controlling combustion in a vapor-burning apparatus.

It comprises a method of utilizing the pressure of the vapor generated by the heat of a burner to control combustion—(a) by regulating the flow of vapor to the burner, (b) by regulating the flow of liquid to the vaporizing device and the flow of vapor to the burner, (c) by cutting off both the flow of liquid to the vaporizing device and the flow of vapor to the burner, (d) by cutting off the flow of liquid to the vaporizing device and the flow of vapor to the burner in the order named, (e) by cutting off the flow of liquid to a preheating device.

I have shown in the accompanying drawings some forms of construction by which my invention may be utilized.

Figures 1 and 3, partly in elevation, partly in vertical section, represent lamps provided with means for practicing my method. Fig. 2 represents a vertical section, on an enlarged scale, of the controlling device shown in Fig. 1.

Similar numerals of reference indicate corresponding parts in the figures.

Referring to Figs. 1 and 2 of the drawings, 35 1 designates a reservoir of a vapor-lamp. 2 designates a vaporizer or generator in which, after the lamp is in operation, the liquid hydrocarbon or fuel, hereinafter designated as an “oil,” is vaporized. 3 designates a superheater 40 or regenerator in which such vapor is superheated and from which it is discharged through the outlet-orifice 4 into a commingling-tube 5, leading to the burners 6. 7 designates a preheating or starting device wherein a temporary flame may be generated to heat the parts 2 and 3. Suitably supported at a convenient distance from the reservoir 1 is a governor-casing 8, in which is a fluid-inlet 9, connected by a tube 10 with the reservoir 1 and opening 45 into an inlet-chamber 11, beneath which is an

outlet-chamber 12, having a fluid-outlet 13, connected by a tube 14 to the generator 2 and by a second tube 15, in which is a cock 16, to the starter 7. Within the chamber 11 and extending substantially above the inlet 9 is a strainer, 55 shown as a perforate or reticulate tube 17, surrounded by a sleeve 18, which may be of any desired fabric. Between the chambers 11 and 12 is a valve-seat 19, against which rests a valve 20, having an upwardly-extending tubular stem 21 and a downwardly-extending portion 22, serving as a guide for a thrust-spring 23, which bears against the valve 20. From the upper tube of the generator 2 rises a tube 24, in which is a cock or valve 25, to a dome 26 65 on the reservoir 1, from which a tube 27 leads to a vapor-inlet 28, communicating with a vapor-chamber 29 in the casing 8. A second tube 30, provided with a cock 31, also connects the generator 2 with the chamber 29. 70 From the vapor-chamber 29 rises a tubular portion forming a passage 36, above which is a diaphragm-box 37, the upper end of which is closed by a cap 38. A rod 39 moves freely in the passage 36 and, as shown, passes 75 through a diaphragm-chamber 40, to the upper shell of which it is tightly secured. To the lower shell of the chamber 40 is secured a collar 41, so that the diaphragm-chamber communicates with the passage 36. A thrust-spring 42 extends between the diaphragm-casing 40 and the cap 38. Attached to the lower end of the rod 39 is a fitting 43, from which depends a second rod 44, the lower threaded end of which slides smoothly on the 85 tubular stem 21 of the valve 20. Lock-nuts 45 are placed on the rod 44, the function of which will hereinafter appear. Pivoted or otherwise attached to the fitting 43 is the stem 46 of a valve 47, which controls the port to 90 the regenerator 3.

The operation is as follows: By momentarily opening cock 16 in tube 15 a small amount of oil is introduced into the preheater or starter 7, the valve 20 being normally open. 95 The heat produced by the combustion of this oil vaporizes that contained in the generator 2, the vapor flowing to the vapor-chamber 29 in the governor 8 either through the tube 24, dome 26, and tube 27 or directly through the 100

tube 30 to the vapor-chamber 29 of the governor 8. I have provided these two means of communication between the generator and the vapor-chamber to insure a free flow of vapor 5 at all times. The vapor flowing through either or both of these tubes into the chamber 29 normally flows out through the tube 48 to the regenerator 3, where it is highly superheated and whence it is forced through the 10 orifice 4. The rushing vapor acts to draw air into the commingling-tube 5, the mixed air and vapor passing to and being consumed in the burners 6. As the diaphragm-chamber 40 communicates, through the passage 36, with 15 the chambers 11 and 29 of the governor, any excess above a predetermined pressure therein will expand the diaphragm and raise the rod 39, fitting 43, rod 44, and valve-stem 46. This permits the spring 23 to close the oil- 20 controlling valve 20, whereby the supply to the generator 2 is temporarily cut off. Any further excess of pressure beyond the point of cutting off the flow of oil will cause further expansion of the diaphragm-chamber 40 and 25 force valve 47 to its seat. This shuts off the flow of vapor to regenerator 3 and extinguishes flame. By adjusting the lock-nuts 45 on the rod 44 the relative motion of the valves 47 and 20 may be accurately determined, while 30 the action of the double device is controllable by varying the pressure on the compression-spring 42 through the cap 38. It is evident that a reduction of pressure in the governor 8 through combustion of the vapor at the 35 burners 6 will permit the spring 42 to reopen the oil-inlet valve 20 and the vapor-outlet valve 47 to the desired extent.

It will be seen that the governing device provides a simple, efficient, and unitary means 40 of controlling the entire flow of both oil and vapor, both of which necessarily pass therethrough. The oil entering at 9 passes through a strainer 17 18, thence past the valve 20 to the outlet 13. The vapor from the generator 45 2 may either pass upward to the reservoir, thence to the vapor-chamber in the governor, or, conversely, it may pass first to the governor, thence to the reservoir. In any case it can only reach the point of combustion by 50 first passing the valve 47, which acts as a safety-valve to modify or entirely cut off the flow when the pressure rises above a predetermined point.

It will be seen that my device is equally 55 efficient to control the flow of oil to the pre-heating device. If too much oil should be permitted to flow thereinto or if the cock 16 should leak, the flame issuing from the mouth of the tube 7 would produce an excess of vapor-pressure in the generator 2, which would of course act to close the valve 20, as before described.

In Fig. 3 of the drawings, 51 designates a reservoir for a liquid hydrocarbon, from which 60 a tube 52, having a check-valve 53, leads to a

vaporizer 54. From the vaporizer a tube 55 leads to a casing 56, shown as mounted on the reservoir and communicating therewith by a passage 57. From the casing 56 a tube 58 leads to a superheater 59. Highly-heated 70 vapor from the superheater passes from the exit-orifice 60 to the mixing-tube 61, thence to the burner 62. A starting or primary heating device 63 is shown as located below the vaporizer 54 and superheater 59 and connected by a valved tube 64 with the reservoir 51. Above the casing 56 is an extension 65, within which is mounted a diaphragm-chamber 66, the stem 67 of which passes freely through a neck 68 into the casing 56. Near the lower end of the stem 67 are two laterally-projecting arms 69 70. The apertured outer end of the arm 69 rides over the stem 71 of a valve 72, by which the flow of the vapor from the vaporizer 54 to the casing 56 is controlled. 75 A collar 73 is secured on the valve-stem 71 below the arm 69. A thrust-spring 74 bears against the collar 73 and tends to close the valve 72. The outer end of the other arm, 70, is secured to a valve-stem 75, whose valve 76 80 closes the outlet from the casing 56 to the tube 58, leading to the superheater 59. A spring 77 normally depresses the arm 70 and holds the valve 76 from its seat. Above the diaphragm-chamber 66 is a thrust-spring 78, operative to reduce the size of the chamber 66, and hence to depress the stem 67. The action of the spring 78 is regulable by an adjusting-screw 79, by which the desired pressure is secured. 85

The operation of the governor or vapor-controlling device is as follows: The vapor generated in the vaporizer 54 by reason of the heat developed either in the preheater 63 or the burners 62 normally rises through the 105 tube 55 to the chamber 56, the valve 72 being kept open by the force of the spring 78, which is set to overbalance the valve-spring 74. This vapor passes freely through the tube 58 to the superheater 59, whence it is mixed with 110 air in the tube 61 and fed to the burners 62. It will be noted that the liquid hydrocarbon flows to the vaporizer 54 from the reservoir 51 through the tube 52. Should too much heat at any time be generated by the burners 115 62, whereby an excess vapor-pressure would be produced in the casing 56, it is evident that this pressure being admitted to the interior of the diaphragm-chamber 66 will expand the diaphragm-chamber and raise the 120 stem 67. This permits the spring 74 to seat the valve 72 and reduces or cuts off the flow of vapor into the casing 56. The vapor already in the casing and in the upper part of the reservoir 51 will be fed to the superheater 125 59 until the excess pressure is exhausted. When the pressure returns to the normal, the diaphragm 66 will contract and the valve 72 will reopen. This releases the vapor-cushion in the vaporizer 54 and tube 55, which per- 130

mits the hydrocarbon to flow into the vaporizer 54, when the generation of vapor is resumed. It will be noted that the vapor retained in the tube 55 and vaporizer 54 forms an effective cushion to prevent any further flow of liquid hydrocarbon through the tube 52 while the valve 72 is closed. If the valve 72 at any time fails to operate properly or if a great excess of pressure should be generated, a further expansion of the diaphragm 66 will close the exit-valve 76 and immediately extinguish the flame, whereby further generation of vapor is of course prevented. It will be seen that this form of construction differs from that first described in that the governor in the present device is operative to control the flow of vaporized hydrocarbon alone. The feed of the liquid from the reservoir to the vaporizer through the tube 52 is normally free and unobstructed, though for convenience a manually-operated valve 53 may be inserted in the tube. On the other hand, the flow of vapor from the generator to the point of combustion—in this case to the lighting-burners through the superheating and mixing devices—is automatically controlled by means operative by the heat of combustion itself. The forms of device herein described are similar to those shown in my pending applications, Serial No. 163,303, dated June 27, 1903, and Serial No. 177,553, dated October 19, 1903, the former of which is a division of my application for a vapor-lamp, Serial No. 154,970, dated April 30, 1903.

It is evident that the method herein described and claimed may be practiced through other forms of construction and for other purposes than those herein shown.

Having thus described my invention, what I claim as new, and desire to secure by Letters Patent, is—

1. The method of controlling combustion in a vapor-burning apparatus, which comprises utilizing the heat of a vapor-burner to generate a further supply of vapor therefor, confining such vapor to produce pressure and utilizing such pressure to limit the flow of liquid to the vaporizing device and to limit the flow of vapor from the place of generation to the burner. 45

2. The method of controlling combustion in a vapor-burning apparatus, which comprises utilizing the heat of a vapor-burner to generate a further supply of vapor therefor, confining such vapor to produce pressure and utilizing the pressure caused by the volume of generated vapor in excess of that required for such combustion to limit the flow of liquid to the generating device and to limit the flow of vapor from the place of generation to the burner. 55

3. The method of controlling combustion in a vapor-burning apparatus, which comprises utilizing the heat of a vapor-burner to generate a further supply of vapor therefor, confining such vapor to produce pressure and utilizing the pressure caused by the volume of generated vapor in excess of that required for such combustion primarily to cut off the flow of liquid to the vaporizing device and secondarily to cut off the flow of vapor from the place of generation to the burner. 65
